UNITED STATES PATENT OFFICE.

CHARLES M. HORTON, OF DULUTH, MINNESOTA.

TRUSS AND BRIDGE.

SPECIFICATION forming part of Letters Patent No. 595,629, dated December 14, 1897.

Application filed November 19, 1896. Serial No. 612,735. (No model.)

To all whom it may concern:

Be it known that I, CHARLES M. HORTON, a citizen of the United States, residing at Duluth, in the county of St. Louis and State of Minnesota, have invented certain new and useful Improvements in Trusses and Bridges; and I do hereby declare the following to be a full, clear, and exact description of the invention, such as will enable others skilled in the art to which it appertains to make and use the same.

My invention relates to that class of bridge-trusses, trussed beams, and supporting columns or posts in which the use of rivets is largely or wholly avoided.

The object of my invention is to maintain the greatest possible proportion of strength in the columns, bridge-trusses, and trussed beams by avoiding to a great degree the use of rivets and other weakening connections in the securing of the component parts of the posts and truss or span and mainly substituting therefor splicing and supporting sleeves, hangers, hook-clips, socket-supports, and similar devices with a conservative use of bolts, and to make the several parts as simple as practicable, so that they may be assembled together easily and rapidly without the usual extensive use of expensive machinery, tools, and labor, maintaining in a high degree strength, durability, and lightness at comparatively small cost.

It consists in certain novel combinations, constructions, and arrangements of parts, as will be hereinafter described and claimed.

In the accompanying drawings, forming parts of this specification, Figure 1 represents a side elevation of my improved bridge truss or span and supporting-columns. Fig. 2 represents a vertical transverse section of the said span, showing the supporting-columns in elevation. Fig. 3 represents a vertical longitudinal section through the upper part of a column and of the shoe for receiving the ends of the chord-beams of adjoining spans. Fig. 4 represents an end elevation, partially in section, of the said shoe. Fig. 5 represents a bottom plan view of the said shoe, the T-beams composing the supporting-columns being shown in section. Fig. 6 represents a plan view of a bottom supporting-plate for the beams of the column to rest upon. Fig. 7

represents a vertical section of the same. Fig. 8 represents a detail in cross-section of a column, showing a binding-sleeve. Fig. 9 is a detail in side elevation of the same. Fig. 10 is a detail in cross-section of a column, showing a binding-sleeve for the upper end thereof. Fig. 11 is a detail side elevation of the same. Fig. 12 represents a detail cross-section of the top-chord I-beam with the hook-clips forming part of my said invention in position thereon and also showing the manner of securing the panel-posts and supporting-rod thereto. Fig. 13 represents a vertical longitudinal section of the same. Fig. 14 represents a detail transverse section through the top-chord I-beam, the splicing and supporting sleeve forming part of my said invention being shown in elevation thereon. Fig. 15 represents a detail in side elevation of the same. Fig. 16 represents a detail side elevation showing the abutment-footing and trunnion-box of said bridge-truss forming part of my said invention and the manner of securing the shore ends of the top-chord I-beam and the bottom-chord links to the trunnion-box and the roller-bearing of said box. Fig. 17 represents an end elevation of the same; and Fig. 18 represents a top plan view of a portion of a bridge-span embodying my invention, the flooring being removed, showing the lateral braces; and Fig. 19 is a detail side elevation of a portion of said bridge, showing the manner of securing the wind-braces in position.

In the drawings corresponding letters refer to corresponding parts.

My invention is well adapted for use in places where a single span is needed or where two or more spans are required, as in the case of a viaduct or similar structures. In this connection I will describe the construction of the columns or posts for supporting the bridge at the termination of the different spans.

A in the drawings designate the T-beams of which the supporting-posts are preferably composed. As shown, they are usually four in number, the legs of the T-beams meeting together and resting in a suitable base-plate B, and the said T's being suitably bound, braced, and held in place, as will be herein-after fully described.

C are inclosing and binding sleeves for

the upper ends of the posts, and E E are bearing-shoes to receive the ends of the top-chord beams of the spans.

The base-plates B B are mounted upon suitable masonry, as at B', and bolted thereto in the usual way, the bolts passing through holes b b in the base-plates for this purpose. The lower ends of the T-beams rest upon the upper surface of the plates B B, preferably as shown in the drawings, with their heads resting against confining-flanges b' b', formed upon the edges of the base-plates. Parallel ribs or raised portions b² b² are arranged upon the base-plates, forming grooves adapted to receive the legs of the T-beams. It will thus be seen that the T-beams are securely held in proper position upon the base-plates when resting thereon. The edge flange b', which is placed toward the inner part of the bridge, is provided with perforated ears b³ b³, adapted to receive and have bolted between them the lower ends of lateral brace-rods b⁴ b⁴, which extend between opposite supporting-posts.

About midway of the height of the posts are secured the binding-sleeves C C, preferably formed in two sections, provided with bolting-flanges c c, by which they are adapted to be secured together, inclosing the T-beams A A, as shown in Figs. 8 and 9. The sleeves C C are provided interiorly with small lugs or projections c' c' in their corners, which are adapted to engage corresponding notches made in the flanges of the T-beams A A, so that the sleeves cannot slip upon the said posts.

The bolting-flanges c c upon the sides of the sleeves C C which extend toward the inner portion of the bridge are adapted to receive and have bolted between them the ends of a cross bracing-beam C', which extends between opposite posts A A. Upon the same side of the sleeves C C, near the top and bottom edges of said sleeves, are formed ears c² c², adapted to receive and have bolted between them the ends of lateral brace-rods between the posts A A, the lower set of ears having secured between them the upper ends of the braces b⁴ b⁴ and the upper set of ears having secured between them the lower ends of the braces b⁵ b⁵. The upper ends of the T-beams are also held together by the sleeves D D, similar to the sleeves C C. These sleeves are provided in their interior corners with lugs or projections d d, adapted to engage notches formed in the flanges of the T-beams A A. By this construction the sleeves D D are prevented from slipping down upon the post.

Upon the side of the sleeves next to the inner portions of the bridge are formed ears d' d', adapted to receive the upper ends of the diagonal brace-rods b⁵ b⁵.

Near the upper edge of the sleeves D D are formed the horizontal lugs d² d², upon opposite corners of said sleeves. These lugs are adapted to receive and have bolted between them the ends of the end links of the lateral braces upon the underside of the bridge-span.

T-beams A A are preferably braced at intervals along their length by brace tie-pieces F F, which are adapted to engage notches 70 formed on the meeting edges of the leg portions of the T-beams, the said brace tie-pieces having notches f f, adapted to inclose a part of the said leg portions, as shown in the drawings.

Upon the upper ends of the T-beams A A are placed the cap bearing-plates E' E', having formed upon their end surfaces the right-angle ribs or projections E² E², forming grooves to receive the upper ends of the leg portions of the T-beams, the head or flange portions of the said T-beams resting against and being confined by the edge flanges E³ E³, also formed upon the under side of the said cap bearing-plates. The upper surfaces of 85 the cap bearing-plates E' E' are recessed, as at e, to receive the rollers e' e'.

Resting upon the rollers e' e' are the shoes E E, which receive the ends of the top-chord I-beams of the truss of the adjacent spans, 90 the said shoes being provided with overhanging flanges e² e², adapted to surround and inclose the upper edge of the cap bearing-plates E' E'. The upper surfaces of the shoes are provided with inclined surfaces e³ e³, upon 95 which the ends of the top-chord I-beams rest, shoulders e⁴ e⁴ being formed thereon to engage the web of said I-beams for holding them securely in position. Trunnion-plates e⁵ e⁵ are formed upon the upper surfaces of said shoes 100 and are adapted to have bolted to them the ends of the bottom-chord links of the adjacent spans.

G G are I-beams laid with the flanges vertical and forming the top chords of said bridge-truss. Each of the top chords of said span on the respective sides thereof is preferably formed of two of these curved I-beams laid end to end with flanges vertical, the upper ends of said beams being spliced by being 110 brought respectively into the opposite ends of the splicing and supporting clip H H in Figs. 1, 14, and 15 at the summit of the longitudinal arch of said truss or span; but said top chord may consist of a single curved 115 I-beam laid with flanges vertical, in which case no splicing-clip will be required; or said chord may consist of more than two curved I-beams similarly laid end to end, with their opposing ends secured, respectively, in said 120 splicing and supporting clips, all within the compass of my said invention. Lateral webs h' h' are formed upon the clips H for increasing the strength thereof. Each of these clips H is preferably formed so as to exactly fit the 125 top and side contours of the T-beams which I employ. Each of the lower ends of the vertical side portions of the clips forms an ear or lug h for the attachment of the panel-posts, braces, &c.

Hook-clips g' g' are used where no splicing is required at other points on the top-chord I-beams G for supporting the panel-posts, brace-rods, and wind-braces. These hook-

clips are preferably formed like the side hook portions of the splice-clips H, being used in pairs, as shown in Fig. 12, and not having a connecting-web, as in the case of said splicing-clips. They are provided with strengthening-webs $g^{11} g^{11}$, similar to the webs $h' h'$ of the splice-clips. Some of these clips $g' g'$ are preferably of the same shape in side elevation as the splice-clips H (shown in Fig. 15) and are more suitable for use in the central portions of the span; but the clips used near the ends of the spans preferably have an elongated top bearing portion, as shown in Fig. 13 at g^{10} , whereby a better grasp or hold upon the top-chord I-beam is obtained for the braces and panel-posts, which are more or less inclined in position. The end clips on the adjacent ends of two spans may be secured together for additional strength by a brace-rod, as at L in Fig. 1 of the drawings.

The plate or clip-hooks $g' g'$ are secured to the respective flanges of the said top-chord beam G by being hooked over the same, the long shanks of said hooks projecting downward beyond the lower edges of said flanges, so as to form ears which are apertured for the passing of the tie-bolts h^3 , which support the upper ends of panel-posts and supporting-rods, as heretofore described, reference being had to Figs. 12 and 13 of the drawings. Shallow notches are cut in the lower flanges of the top-chord beam at points where said tie-bolts pass through, thus binding the hook-clips as well as the splice-clips close to the top-chord beam and preventing their slipping longitudinally out of position along said top chord. The ears upon both the splice-clips H and the hook-clips G' are reinforced upon their inner faces by segmental ribs or raised portions h^4 , and the under sides of the flanges are notched to fit upon the upper ends of these ribs in order to lock the said clip in position.

G' G' are I-beam panel-posts secured at their upper ends in said splicing and supporting clips H or in hook-clips g' , respectively, by tie-bolt h^3 passing through the ears h of said splicing-clip H or the ears, respectively, of said hook-clips g' and through both flanges of said panel-post, a small portion of the web of said panel-post at the upper end thereof being cut away to admit of the passage of said tie-bolt h^3 through the flanges, substantially as shown. The lower end of said panel-post is supported and secured by bottom-chord tie-bolt g^6 , which passes through the floor-beam hangers h^7 and the enlarged apertured ends of the bottom-chord links g^2 and supporting-rods and through the flanges of said panel-post, the web of said post at the foot thereof being slightly cut away to admit of the passage of said bolt g^6 through the said flanges, substantially as shown in detail in Fig. 19 of said drawings.

Attaching-clips K K are secured to the upper and lower ends of the panel-posts G' G', being so formed as to fit over the web of said

posts between the flanges, as shown in Figs. 12 and 13, and being secured to the said web by bolts $k k$, passing through the said clips K and the web. Extending from the body portion of the clips K are enlarged flattened eye portions K' K', having perforations registering with the perforations in the flanges of the panel-posts G' G', so that the tie-bolts h^3 and g^6 , respectively, at the top and bottom, will pass through said eyes K' K'. It will thus be observed that the clips K K add greatly to the security of the attachment of the ends of said panel-posts and enable said posts to stand a greater strain.

$g^2 g^2$ are bottom-chord links, preferably flat and set on edge, having enlarged apertured ends secured at the shore ends respectively to the trunnion-plates I, as in Figs. 16 and 17 and hereinafter described, by suitable bolts g^7 , passing through said trunnion-plates and through the shore ends of said links and having their other ends secured, respectively, to the supporting-rods at each panel by the tie-bolt g^6 , there being two bottom-chord links to each panel of said truss, decreasing in size and weight in the respective panels of said truss from the respective ends of said truss toward the center of the same.

$g^3 g^4 g^5$ are supporting, bracing, or tension rods, perfectly flat and provided with enlarged apertured ends. They are secured at their upper ends in said splicing-slips or hook-clips, as the case may be, by said tie-bolts h^3 . The tie-bolt g^6 connects together at each panel the bottom-chord links, bottom ends of the several supporting-rods, the foot of panel-post, and floor-beam hangers. The end bottom-chord links $g^2 g^2$ at the adjacent ends of two spans are secured to the bolt, passing through the trunnion-plates $e^5 e^5$ of the shoes E E, as hereinbefore described.

The wind-bracing of the bridge is composed of T or angle irons running up from the ends of the floor-girder beams to the inside of the clip on the top chord. The said T-irons g^8 are secured at the upper ends against the inner faces of outer ears $h h$ of said splicing and supporting clips H or against the corresponding ear of hook-plates g' , as the case may be, by tie-bolts $h^3 h^3$, said bolts passing through the lower flange of each of said T-braces, which are apertured and turned up against the inner faces of said ears, the other flange of said braces being cut away for a short distance at its upper end to admit of the passage of said bolts, said braces extending downward and outward to the outboard ends of the floor-girder beams J J and being bent up at their lower ends and secured to the upper faces of the upper flanges at the outer ends of said floor-beams by suitable bolts or rivets passing through the horizontal flanges of said T-braces at that point on either side of the vertical flanges thereof and through the upper flanges of said floor-beams on either side of the webs thereof.

The shore ends of bridge-spans constructed

like my device rest upon shoes or trunnion-boxes similar to those upon the top of the supporting-columns, as described above. The trunnion-plates I are erected upon a base-plate i^3 and are integral therewith. An inclined surface i^8 is formed on the upper surface of the base i^3 to receive the shore end of the beam G , as hereinafter described.

i^2 i^2 are rollers beneath the trunnion base-plate i^3 , similar to the rollers $e' e'$, the rollers resting in a foundation channel-plate i^6 .

i^4 i^4 are anchor-bolts adapted to extend into abutment masonry and projecting through flange or margin of foundation-plate i^6 , holding said foundation-plate down on abutment i^5 .

The rollers i^2 i^2 are preferably spaced or prevented from rubbing against each other by plates i^7 i^7 , provided with journal-bearings adapted to receive journals formed upon the ends of the rollers. Thus they are not only kept from touching each other, but are properly spread beneath the base i^3 to thoroughly support it in every part.

25 The floor girder-beams J J are each supported at each end by one or more hangers or yokes h^7 h^7 , passed over the tie-bolt g^6 , the lower ends of which pass through the flanges of the said floor-beams and are screw-threaded 30 to receive nuts of suitable strength.

The bridge-span is braced laterally by rods j j , preferably placed diagonally between adjacent floor-beams and provided with right and left threaded nuts or turnbuckles j j , by 35 which said rods may be adjusted or tightened. The ends of the brace-rod j j are preferably formed with double eyes j^2 j^2 , adapted to be placed one above and one below the flanges of the floor-beam J and to have the hangers h^7 pass through them for bolting them securely to said floor-beams.

It will be seen from the above description that bridges, viaducts, &c., constructed in accordance with my invention are adapted to 45 be put together without extensive boring and consequent weakening of the truss-beams and that all the parts can be easily and expeditiously put together and in a manner well suited to meet all the strains to which they 50 may be subjected.

It will of course be apparent that I can vary the construction of the splicing and supporting clips, trunnion-boxes, floor-beam hangers, supports, anchorages, and fastenings required 55 to unite the parts to form a durable, light, and efficient bridge-truss or similar structure without departing from the spirit of my invention.

Having now described my invention, what 60 I claim as new, and desire to secure by Letters Patent, is—

1. In a truss the combination of top-chord beams, hooked clips hung from the edges of the said beams and adapted to secure posts, supports and braces to said top-chord beams 65 without passing bolts or pins through the

same and thereby weakening them, substantially as described.

2. In a truss the combination of top-chord beams, splicing-clips applied thereon for locking them in place, and adapted to secure suitable posts, supports and braces to said beams without weakening the same by bolt-holes and vertical webs formed upon said clips for strengthening them, substantially as described. 70

3. In a truss the combination of arched I-beams, forming a top-chord beam, splicing-clips adapted to fit the contour of said beams for locking the ends of the same in place, 80 vertical webs formed upon the said clips for strengthening them, and means for securing posts, supports, tie-rods and braces to said clips, the construction being such that the arched beams are not weakened by perforations for bolts, pins or the like, substantially as described.

4. In a truss, the combination of arched I-beams, hooked clips adapted to fit upon the flanges of said I-beams and be locked thereon 90 and means for attaching supports, posts, and braces, the said clips, the construction being such that the arched beams are not weakened by perforations as for bolts, pins or the like, substantially as described. 95

5. In a column or post for supporting structures, the combination of a plurality of angle-beams, meeting at a central point and divided clips adapted to be bolted together so as to inclose the said beams for holding them 100 together, the construction being such that the said angle-beams are not perforated as for bolting and thereby weakened, substantially as described.

6. In a column for supporting structures, 105 the combination of a plurality of angle-irons, the legs of which meet at a central point, a base-plate provided with grooves adapted to fit the end contour of said angle-irons and laterally-extending ears upon said base-plate 110 for receiving and securing the end of the brace-rod, and divided clips adapted to be bolted together so as to inclose the said beams and bind the said irons together without perforating them for bolting, substantially as described. 115

7. In a supporting column or post the combination of a plurality of angle-irons, the legs of which meet at a central point, grooved plates for holding the ends in position and sleeves formed of divided clips provided with external bolting-ears, the said clips being adapted to be bolted together so as to inclose said irons and bind them together without perforating them for bolting, substantially as described. 125

8. In a support for bridges, viaducts or the like, the combination of columns comprising a plurality of T-beams having their leg portions turned toward each other, end plates 130 having grooves for holding the ends of said beams in place, sleeves consisting of divided

clips having external bolting-flanges whereby the clips are adapted to inclose said beams and to bind them together, projections on said clips adapted to engage notches in the 5 edge of flanges of the beams to prevent slipping and means secured to said plates and sleeves for bracing the said columns laterally, the construction being such that the said T-beams are not perforated as for bolting or 10 riveting, and consequently weakened, substantially as described.

9. In a column for bridges, viaducts or the like, the combination of a plurality of angle-irons meeting at the center, means for binding 15 said angle-irons together without passing bolts through the same, a cap-plate adapted to fit upon the upper ends of said irons, and provided with a channel or recess upon its 20 upper surface adapted to receive rollers, and a shoe resting upon said rollers, adapted to receive and support the end of a truss-beam, without bolting, substantially as described.

10. In a column for supporting adjacent 25 spans or trusses the combination with a suitable cap-plate, of a shoe or trunnion box for supporting the ends of the top-chord beam of said spans, roller-bearings interposed between the said cap-plate and shoe, overhanging flanges upon said shoe completely covering 30 the rollers and the cap-plate for keeping out water or ice, and trunnion-plates upon said shoe adapted to support the end bottom-chord links of said spans, substantially as described.

11. In a truss the combination with a top- 35 chord beam, of panel-posts adapted to connect the said top-chord beam with the floor-beam of the said truss, clips having bolting-flanges adapted to inclose and be secured to the web of said panel-posts, ears at right angles to the 40 said flanges for securing the same to the top and bottom tie-bolts, substantially as described.

12. In a truss the combination with a top-chord beam, of hooked clips hung from the 45 opposite edges of the same, depending ears upon said clips extending below the top-chord beam and adapted to receive a connecting-bolt, for locking them in place, said bolt being adapted to support the panel-posts, braces 50 and wind-braces, substantially as described.

13. In a truss the combination of arched top-chord beams having a continuous curved form, roller-bearings having shoulders and inclined surfaces upon their upper sides 55 adapted to receive and support the ends of

said top-chord beams and means for securing posts, supports, braces and beams to said top-chord beams, substantially as described.

14. In a truss for bridges the combination with top-chord beams of shoes having inclined upper surfaces and shoulders thereon adapted to receive the shore ends of said beams, channel base-plate secured to the shoe-abutments, and rollers interposed between said shoes and channel-plates, substantially as described. 60

15. In a truss for bridges the combination with top-chord beams and bottom-chord links, of shoes adapted to receive the shore ends of said beams having inclined surfaces upon the 70 said shoes for receiving the end thrusts of said beams, channel-plates secured to the shore-abutments, rollers interposed between said shoes and channel-plates, and trunnion-plates formed on said shoes adapted to have 75 secured to them the shoe ends of the bottom-chord links of the truss, substantially as described.

16. In a truss the combination with top-chord beams, of panel-posts secured thereto, 80 clips having bolting-flanges adapted to inclose and be secured to the webs of said panel-posts, and ears at right angles to the said flanges, bolts passed through the lower ends of said posts and said ears, I-beams for supporting the floor of the truss, yokes passing over the said tie-bolts and passing through the flanges of the said floor I-beams and means for securing the said yokes to the said flanges, substantially as described. 85

17. In a truss-bridge or viaduct the combination with top-chord beams, of panel-posts, I-beams for supporting the floor of the truss, yokes at the lower end of said panel-posts passing through the flanges of the said I-beams 95 for securing the floor-beams of said bridge, or viaduct to said posts, and diagonal brace-rods interposed between said floor-beams, and having bifurcated ends adapted to embrace the flanges of said floor-beams, the said bifurcated ends having apertures to receive the said yokes for laterally bracing the bridge, substantially as described. 90

In testimony whereof I affix my signature in presence of two witnesses.

CHARLES M. HORTON.
